DEVICE TO AID TURNING OF STEERING WHEELS

John L. Barr, Chevy Chase, Md.

Application May 24, 1934, Serial No. 727,351

13 Claims. (Cl. 180—1)

My invention relates to means for facilitating the steering of cars and in particular to means for facilitating the turning of steering wheels in cramped quarters, such as in parking and unparking cars in confined spaces.

It is an object of the invention to facilitate the turning of the steering wheels of an automobile.

Another object of the invention is to provide a simple, durable mechanism which is easily repaired and replaced and in which the power for relieving the weight at least in part on at least one of the steering wheels may be derived either through the intake manifold of an internal combustion engine or from a moving part of the engine which drives the vehicle.

In one form of my device I employ a system which is operated from the intake manifold of the engine. In this particular form as shown, I have the intake manifold connected to a mechanism which will increase the power which may be applied to the lift mechanism. In this form of device, I connect the intake manifold to a cylinder in which there is a moving piston. This cylinder is relatively large and the piston is caused to move under the pressure differential produced through connecting one side of the piston to the intake manifold. This movement of the piston is used to compress at high pressure a fluid such as oil which in turn is used to operate another piston which is attached to the compression element of the lift mechanism.

In another form of device which I have shown, I use a rotating part of the engine such as the fly wheel of the generator, though any other suitable moving part could be employed as the source of power. In the form shown I have employed a belt which fits over the fly wheel and the generator pulley of this engine, and this belt is used to rotate the moving parts of a rotary pressure pump which sends fluid under high pressure to the cylinder which operates the compression element of the device.

In the drawings:

Fig. 1 shows a side elevation of my device as applied to the front wheels of an automobile;

Fig. 2 is a detail view partly in section taken through the longitudinal axis of the compression element and its operating cylinder;

Fig. 3 is an end view of the mechanism which delivers the oil under high pressure to the lift mechanism;

Fig. 4 is a view taken through the longitudinal axis of the mechanism shown in Fig. 3;

Fig. 5 is a sectional view taken along the line

5—5 of Fig. 4, looking in the direction of the arrows;

Fig. 6 is a view taken along line 6—6 of Fig. 2, looking in the direction of the arrows;

Fig. 7 is a detail view of the operating valve 5 for controlling the operation of the device, the view being shown partly in section;

Fig. 8 is a side elevation of another form of my device;

Fig. 9 is a sectional view taken through the rotary pump of the modification of Fig. 8, the view being along the line 9—9 of Fig. 11, looking in the direction of the arrows;

Fig. 10 is a view taken along line 10—10 of Fig. 9, looking in the direction of the arrows;

Fig. 11 is a view taken along line 11—11 of Fig. 9, looking in the direction of the arrows;

Fig. 12 is an exploded view taken along the longitudinal axis of the compression element and its operating cylinder.

Referring to the drawings I have shown an automobile frame 1, the automobile being provided with a floor board 2 and a dash 3. Passing through the floor board 2 is a steering post 4. Mounted on the frame 1 is an internal combustion engine 5 which has an intake manifold 6. A front axle 7 is carried by springs 8 on the frame 1.

Connected to the intake manifold 6 is a pipe 9 which communicates with a valve structure 11. From the other side of the valve structure 11 passes a pipe 12 which, through a fluid tight fitting 13, communicates with the interior of a cylinder 14. The cylinder 14 is provided with a cylinder head 15 which may be attached to the cylinder 14 by screws 16. The cylinder head 15 is provided with an extended central portion 17 which has a port 18 opening to the atmosphere. Within the cylinder is a piston which I have designated generally by numeral 19. This piston is of the usual fluid type construction and attached to this piston through the usual attaching means, indicated by numeral 20, is a piston rod 12.

The other end of the cylinder 14 is provided with an annular hollow extended portion 22 which has a flange 23. To the flange 23 is bolted by means of bolts 24 a flange 25 of a smaller cylinder element 26. Suitable packing 27 may be inserted between the flange elements 23 and 25 to make a fluid tight joint. The piston rod 21 is adapted to closely fit into the cylinder 26. The piston rod 21 passes through a suitable packing gland 28, which it is not necessary to describe in detail. Surrounding the piston rod 21 is a

helical compression spring 29 which tends to hold the piston 19 in the position shown in Fig. 4. Surrounding the cylinder 26 is a reservoir 31 provided with an apertured filling tap 32. This reservoir 31 is provided with an end closure member 33. Fluid tight connections may be made where the reservoir contacts adjacent structure, as is plainly apparent in Fig. 4.

The cylinder 26 is formed with a valve head construction which comprises a central aperture 34, a conical valve seat 35 and port 36 communicating directly therewith, and a port 37. Against the conical seat 35 is adapted to bear a ball 38 which is pressed downward by a spring 39 held in place by means of a screw tap 41. The valve head is adapted to be screwed as indicated at 42 into the closure 33 of the reservoir 31. A flexible pipe 43 is attached by means of suitable coupling 44 to the valve head, as is plainly shown in Fig. 4.

The valve 11 before referred to comprises a fitting having ports 45 and 46. The pipe 9 through a suitable connection indicated generally by numeral 47 communicates with port 45 and the pipe 12 through a suitable similar fitting connection which is indicated generally by numeral 48 communicates with port 46. The valve 11 is provided with extensions 49 and 51 and a central aperture in these extensions, indicated by numeral 52. A screw tap 53 closes the extension at one side and through the screw tap 53 is adapted to slide valve stem 54.

On the valve stem 54 are located fluid tight sliding members 55 and 56. Communicating with aperture 52 is a port 56' which communicates with the atmosphere. To the valve stem 54 is pivoted at 57 an operating rod 58. To the operating rod is attached collar 59 to which is also attached a tension spring 60 that is attached, as indicated at 61, to the valve 11.

The operating rod 58 is pivotally attached at 62 to a bell crank lever 63 which is pivoted at 64 and which has one arm provided with a foot pedal 65. The arm that carries foot pedal 65 fits through aperture 66 in the floor board 2 of the car. By pressing down on foot pedal 65 operating rod 58 will be pulled against the tension of spring 60 to permit communication between port 45 and port 46. In this position port 56' is closed. Upon release of the foot pedal the spring 60 positions the parts as indicated in Fig. 7 and closes communication between port 45 and 46. Port 46, however, is in communication with the atmosphere through port 56'.

The lift mechanism comprises a compression element 67 which has a female member 68 internally screw threaded and a male member 69 externally screw threaded. A lock nut 71 is adapted to hold the male and female members in fixed relationship when the length of the compression element has once been adjusted. The male member carries a ball 72 at its end which fits within a socket formed within foot piece 73. A holding plate 74 fits over the top of the ball 72 and prevents its egress from the socket and foot piece. The plate 74 is held in place by means of screws 75.

The female member 68 is provided with an extension 76 which carries a ball 77 which fits within a socket formed in a fitting 78 that may be integrally formed with piston 79.

The fitting member 78 is provided with a groove or aperture 81 permitting the compression element to be moved upward into the dotted line position indicated in Fig. 1. A retaining brad 82

holds the ball 77 in position and is itself held in place by means of screws 83.

The piston 79 is provided with a piston head assembly which I have indicated generally by numeral 84. This is of the usual fluid tight type. The piston head 84 is adapted to fit in a cylinder 85 to which is screw threaded cylinder head 86. The cylinder head 86 is held by means of clamping member 87 to the axle 1. The cylinder 85 is provided with a head fitting 88 at its other end, which is screwed onto the exterior wall of the cylinder 85 and which forms a fluid tight connection with cylinder wall 85. Packing 89 may be employed to insure a fluid tight fit. In this cylinder head construction 88 there is provided a port 90 communicating with the interior of the cylinder and an extension 91 to which is adapted to be attached the flexible pipe 43. The cylinder head construction 88 is adapted to fit under a spring pad construction 92 which is carried by axle 1. This construction is adapted to firmly hold the cylinder in place.

Attached to the compression element by means of a pivoted fitting 93 is a Bowden wire 94 which passes through a sheath 95 and is adapted to be reeled up by means of a reel construction 96 that may be located on steering post 4. An anti-rattle spring 97 is adapted to bear against the foot of the compression element when it is in its raised position as indicated in dotted lines in Fig. 30 1, thereby preventing rattling or undue movement of the parts. The spring 97 may be bifurcated at its end and fit over the male portion 69 of the compression element 67. The sheath 95 for Bowden wire 94 may be mounted on a suitable fitting 98 which is carried by the anti-rattle spring 97.

In operation the Bowden wire is unreeled from its up position to permit the compression element 67 to fall into the position indicated in dotted lines in Fig. 1. When the device is not in use, compression element 67 occupies the other position indicated by dotted lines in Fig. 1, and Bowden wire 94 is reeled up tight so that the foot of the compression element bears firmly against anti-rattle spring 97. The anti-rattle spring 97 can be carried on the spring pad which is formed on axle 1 as indicated in Fig. 2.

Let us assume that the compression element has dropped to the said position shown in dotted lines in Fig. 1, the operator steps on foot pedal 65, causing parts of the valve mechanism 11 to move so that communication between ports 45 and 46 is established, thereby throwing pipe 12 into communication with intake manifold 6. This causes suction on piston head 19 in cylinder 14. That is to say, atmosphere pressure entering the cylinder through port 18 will force the piston head 19 to the left with the parts viewed from the position in which Fig. 4 is taken. This drives piston 21 to the left and compresses fluid, oil in this case, in the cylinder 26.

Compressed oil is ejected through port 37 to flexible pipe 43 where it passes downwardly, entering cylinder 85 and pressing downwardly on the piston head 84 in that cylinder, thereby compressing a spring 99 in that cylinder. This causes the compression element to be moved downwardly into contact with the roadbed, then to relieve the weight at least in part on at least one of the steering wheels of the vehicle. This relief of weight as indicated permits the steering wheels to be more readily turned which is of advantage in parking or unparking cars in confined spaces.

Upon release of foot pedal 65 the parts in the

valve 11 will assume the position shown in Fig. 7 and the pressure of the spring in the cylinder for the compression element as well as the weight of the car will force the oil from that cylinder back into cylinder 26. The spring 29 in the vacuum cylinder 14 also aids in moving the parts into the position shown in Fig. 4 of the drawings, air entering through pipe 12 which is drawn from the atmosphere through port 56'. The ball valve 35 5 will permit replacement of any oil necessary to fill cylinder 26.

The reel on the steering post may then be brought into action to raise the compression element to the "up" position shown in dotted lines in Fig. 1.

It is to be noted that the foot of the compression element is universally connected to the compression element and that the compression element itself is universally connected to its piston. 10 This is of advantage in permitting adjustment to strain during the turning of the wheels, and in allowing the vehicle to be driven off the device without injury to either the device or the vehicle when the device is being used.

15 The various motions which may be compensated for during the turning of the steering wheels are fully set forth in my copending application Serial No. 724,168, filed May 5, 1934.

20 Referring to Fig. 8, I have shown a modification of the device. In this form of device the cylinder 85 is somewhat differently mounted on the axle 7. The head fitting 88 is provided with a bolt extension 101 and the cylinder head 86 at the other end is provided with a bolt extension 102. 25 A holding plate 103 is held in place by means of nuts 104 on either end of the extensions 101 and 102. In this form the anti-rattle spring 97 is mounted directly by some suitable attaching means 105 on the cylinder head 88. There is provided a fitting 106 which is screwed into the top of the cylinder head 88 and to which is attached the flexible pipe 43.

25 In the drawings I have shown the motor 5 provided with a fan 107 which carries a fan pulley 108. The fan pulley is driven by belt 109 which passes down over pulley 111 and is carried by a crank shaft. The belt 109 also fits over pulley 112 which is adapted to drive a generator 113. The pulley 112 has an extension 114 over which fits a belt 115 that passes over another pulley 116 which is mounted on a shaft 118 of a rotary pump.

30 The rotary pump comprises a casing 119 which has a reservoir 120. The casing is adapted to be attached as indicated at 121 to some suitable portion of the motor or frame. The reservoir 120 is provided with a filling tap 120' through which oil may be introduced into the reservoir. The bottom of the reservoir 120 communicates with inlet port 122 (see Fig. 10) that passes into a chamber 60 containing rotary pump gears. There is one rotary pump gear 123 mounted on the shaft 118 and keyed thereto, and another rotary pump gear 124 mounted on a shaft 125. The gear 124 meshes with gear 123. Both gears turn in a gear casing 65 126 formed in the casing.

35 This type of rotary gear pump is well known in the art. The teeth of the gears are so arranged that oil is picked up by gear 123 between the teeth when the shaft 118 is rotated to move the gear as indicated by the arrows to the right in Fig. 9, i. e., counterclockwise. The oil between the teeth of the gears is moved around and when the teeth of the gear 123 mesh with the teeth of gear 124, the oil is squeezed out between them. Gear 124 turns in a clockwise direction and the oil is picked up

between the teeth and squirted out between the teeth of gears 124 and 123.

The oil escapes from chamber 126 through an outlet port 127 into valve chamber 128 thence into a port 129 which communicates with a fitting 130 5 to which is attached the flexible tubing 43. The valve chamber 128 has a sliding valve arrangement (see Fig. 11) comprising a stem 131 carrying sliding heads 132 and 133. Helical spring 134 tends to hold the parts in the position shown in Fig. 11. Through a suitable fluid tight connection 136 passes a reduced portion 137 of the valve stem 131. Pivoted at 138 (see Fig. 8) on this reduced portion 137 of valve stem 136 is an operating rod 139 which is pivoted at 141 to one arm of a bell 15 crank lever 142 which is pivoted at 143 on some suitable portion of the motor or car. The bell crank lever 143 is provided with an arm which passes through an aperture 144 in the floor board 2 of the car and which carries a foot pedal 145. 20

25 Entering the valve chamber 128 is a return port 146 which communicates with a chamber 147 that is provided with a port 148 that communicates with reservoir 120. In chamber 147 is a port 149 having a conical seat provided above it against which bears ball 150 that is downwardly pressed by means of spring 151 which is held in place by adjusting screw plug 152. Port 149 communicates with outlet port 127.

30 With the parts in inoperative position with the compression element 67 in the raised position and foot pedal 145 in the position shown in Fig. 8, gears 123 and 124 feed oil from the chamber 126 through outlet port 127 into valve chamber 128, whence the oil idles through return port 146 into chamber 147 and through port 148 back into reservoir 120, and thence again through inlet port 122 to repeat the cycle.

35 Let us assume, however, that the operator has lowered the compression element 67 into the position shown in Fig. 8 so that its foot rests against the ground. The operator steps on pedal 145 which pulls on rod 149 and moves the valve stem 131 into a raised position against the tension of spring 134. This causes valve member 133 to 40 cover return port 146. The fluid then from the gear chamber 126 passes through the port 129 into flexible tube 43 and pushes the piston 84 into a lower position to relieve the weight at least in part on at least one of the steering wheels of the 50 car. When the piston 84 has reached the down position against the tension of spring 99, oil will then be forced by the ball 150 at the top of port 149 and can pass through port 148 back into reservoir 120. 55

60 By suitably regulating the tension of spring 151 through adjustment of screw tap 152 the amount of pressure necessary to raise ball 150 from the conical seat can be regulated, so that sufficient pressure can be generated to permit ready operation of the device to relieve the weight as desired, yet when pressure is too high oil will pass from the intake to the output side of the pump past ball 150.

65 Upon release of pressure on pedal 145 the spring 134 pulls the valve stem 131 and its associated parts again into the position shown in Fig. 11, and oil is forced by reason of the weight of the car and the tension of spring 99 in cylinder 85 back through port 129 into valve chamber 128. 70 This oil, together with the oil which is idling through the pump can return through port 146 into chamber 147 and through port 148 back into reservoir 120. The operator can then reel up the 75

compression element 67 to its position indicated in dotted lines in Fig. 8.

While I have shown and described the preferred embodiment of my invention, I wish it to be understood that I do not confine myself to the precise details of construction herein set forth, by way of illustration, as it is apparent that many changes and variations may be made therein, by those skilled in the art, without departing from the spirit of the invention, or exceeding the scope of the appended claims.

I claim:

1. In an apparatus of the class described, a pump driven from a moving part of a motor to furnish a source of fluid under pressure, and a lift mechanism operated by fluid from the pump to relieve the weight at least in part on at least one of the steering wheels of a vehicle, comprising a cylinder adapted to receive the fluid under pressure, a piston in the cylinder, a compression element and support means carried by the piston and permitting universal movement of the top of the compression element.
2. In an apparatus of the class described for a motor driven vehicle having steering wheels, a rotary pump driven from a moving part of the motor to furnish a source of fluid under pressure, and a lift mechanism operated by fluid from the rotary pump to relieve the weight at least in part on at least one of the steering wheels of the vehicle, comprising a cylinder adapted to receive the fluid under pressure, a piston in the cylinder, a compression element and support means carried by the piston and permitting universal movement of the top of the compression element.
3. In an apparatus of the character described for a motor driven vehicle having steering wheels and a generator, a rotary pump to furnish a source of fluid under pressure, means connecting a moving part of the generator and the pump to operate the pump and a lift mechanism operated by fluid from the pump to relieve the weight at least in part on at least one of the steering wheels of the vehicle, comprising a cylinder adapted to receive the fluid under pressure, a piston in the cylinder, a compression element, and support means carried by the piston and permitting universal movement of the top of the compression element.
4. In an apparatus of the character described a compression element, a cylinder, a piston for the compression element adapted to move in the cylinder, a pump driven from a moving part of the motor to furnish fluid under pressure to operate the piston, support means carried by the piston and permitting universal movement of the top of the compression element.
5. Apparatus of the character described comprising a compression element, a cylinder, a piston for the compression element adapted to move in the cylinder a universal connection between the element and the piston, a rotary pump driven from a moving part of the motor to furnish fluid under pressure to operate the piston, and means permitting idling of the fluid in the pump when the compression element is in its downwardly extended position.
6. Apparatus of the character described comprising a compression element, a piston for the compression element adapted to move in the cylinder a universal connection between the element and the piston, a rotary pump, means connecting a moving part of a generator to the pump to operate the pump means connecting the pump, to the cylinder to relieve the weight at least in part

on at least one of the steering wheels of the vehicle, and means permitting idling of the fluid in the pump when the compression element is in its downwardly extended position.

7. Apparatus of the character described comprising a compression element, a cylinder, a piston for the compression element adapted to move in the cylinder, a universal connection between the element and the piston, a pump driven from a moving part of a motor to furnish fluid under pressure to operate the piston, spring means tending to return the piston to an initial position, means to drop the compression element into operative position, and means to permit idling of the fluid in the pump when the compression element is in its raised inoperative position.

8. Apparatus of the character described comprising a compression element, a cylinder, a piston for the compression element adapted to move in the cylinder, a universal connection between the element and the piston, a rotary pump driven from a rotating part of a motor to furnish fluid under pressure to operate the piston, spring means tending to return the piston to an initial position, means to drop the compression element into its operative position, and means to permit idling of the fluid in the pump when the compression element is raised into its inoperative position.

9. Apparatus of the character described comprising a compression element, a cylinder, a piston for the compression element adapted to move in the cylinder, a universal connection between the element and the piston, a rotary pump, means connecting a moving part of the generator to the pump to operate the pump, means connecting a rotary pump and the cylinder, spring means tending to return the piston to an initial position, means to drop the compression element into its operative position, and means to permit idling of the fluid in the pump when the compression element is raised into its inoperative position.

10. Apparatus of the character described, comprising a compression element, a cylinder, a piston for the compression element adapted to move in the cylinder a universal connection between the element and the piston, a pump driven from a moving part of the motor to furnish fluid under pressure to operate the piston, means to drop the compression element to operative position, valve means to permit idling of the fluid in the pump when the compression element is raised into its inoperative position, and valve means permitting idling of the fluid in the pump when the compression element is in its downwardly extended position.

11. Apparatus of the character described, comprising a compression element, a cylinder, a piston for the compression element adapted to move in the cylinder a universal connection between the element and the piston, a pump driven from a moving part of the motor to furnish fluid under pressure to operate a piston, valve means permitting idling of the fluid in the pump when the compression element is in its downwardly extended position, and means to lock the fluid in the cylinder when the compression element is in its fully extended position.

12. Apparatus of the character described, comprising a compression element, a cylinder, a piston for the compression element adapted to move in the cylinder a universal connection between the element and the piston, a pump driven from a moving part of a motor to furnish fluid under pressure to operate the piston, spring means tending to return the piston to an initial position,

means to drop the compression element into operative position, valve means to lock the fluid in the cylinder when the compression element is in its fully extended downward position, and means to permit idling of the fluid in the pump when the compression element is raised into its inoperative position.

13. Apparatus of the character described, comprising a compression element, a cylinder, a piston for the compression element adapted to move in the cylinder a universal connection between the element and the piston, a rotary pump driven from a moving part of the motor to furnish fluid

under pressure to operate the piston, spring means tending to return the piston to an initial position, means to drop the compression element into its operative position, valve means to permit idling of the fluid in the pump when the compression element is raised into its inoperative position, valve means permitting idling of the fluid in the pump when the compression element is in its downwardly extended position, and valve means to lock the fluid in the cylinder when the compression element is in its downwardly extended position.

JOHN L. BARR.
